UNITED STATES PATENT OFFICE.

JOHN GRANT, OF LOS ANGELES, AND STEWART L. CAMPBELL, OF BERKELEY, CALIFORNIA; SAID CAMPBELL ASSIGNOR TO SAID GRANT.

PIPE OR CASING TONGS.

Application filed November 26, 1923. Serial No. 676,987.

To all whom it may concern:

Be it known that we, JOHN GRANT, a citizen of the United States, and resident of Los Angeles, in the county of Los Angeles and State of California, and STEWART L. CAMPBELL, a citizen of the United States, and resident of Berkeley, in the county of Alameda and State of California, have invented new and useful Improvements in

10 Pipe or Casing Tongs, of which the following is a specification.

This invention relates to a tool for gripping work and pertains particularly to a wrench or tongs which is adapted to grip 15 cylindrical work, such as pipe, casing, rods, and the like. The invention, for illustrative purposes, is shown herein as embodied in a casing or pipe tongs commonly employed in oil well work.

20 The invention has for its principal object the provision of a tool of the character described, which on being applied to the work will embrace the latter and may be locked thereto, then will grasp the work to prevent relative turning of the work and tool in either of its directions and will increase the grip with increase of turning stress. Another object of this invention is to provide a 25 tool having a gripping device operable at will to initially grip the work against turning in either direction and to entirely release the grip when so desired. A further object of this invention is to provide a tool having a locking device which may be 30 released by the operator from the position at the handle of the tool.

These objects together with other objects and corresponding accomplishments are obtained by means of the embodiment of our 40 invention illustrated in the accompanying drawing, in which:

Fig. 1 is a plan view of the tool in work embracing position with the lock closed and the gripping device in neutral position; Fig. 2 is a side elevation as seen looking in the direction of the arrows 2—2 in Fig. 1; Fig. 3 is a section taken on the line 3—3 of Fig. 1 showing fragments of the tool on an enlarged scale; Fig. 4 is a fragmentary section 50 on an enlarged scale taken on the line 4—4 of Fig. 1; Fig. 5 is a plan view showing the tool in work embracing position with the lock just closing, the dotted lines showing the lock jaws in open position; Fig. 6 is a section 55 showing in full lines the parts and work in

embracing position and the gripping device in neutral position, the dotted lines showing the gripping device in position to initially grip the work preparatory to turning in the direction shown by the arrow; and Fig. 7 shows the position of the parts as in Fig. 6 with pressure applied to the handle of the tool to turn the same in the direction of the arrow.

Referring more particularly to the drawing, the handle of the tool is indicated by A. The jaw head is indicated generally by B and is adapted to embrace the work. C indicates generally the lock for fastening the jaws together about the work and D the grip device.

The handle A is formed of a lever 8 at the top of which is a pivot bolt 9. To the side of the pivot bolts are elongated slots 10 and 10' similar in form. Extending through the elongated slots 10 and 10' are pins 11 and 11'. Mounted upon each pin on opposite sides of the handle head are links, the pairs of the links being indicated by 12 and 12'. Spanning each pair of links at the upper end and connecting them is a pin upon which are pivotally mounted jaws 13 and 14. The pins are indicated by 15 and 15'. The pins overhang the ends of the links as best shown in Fig. 3. Covering the links and jaws are plates 16 and 16' of crescent form. These plates are provided with elongated slots in which the pins 15 and 15' are disposed. Ears are provided upon the plates at their edges and have registering bolt openings so that spacing bolts 17 and 17' which connect the plates may be inserted.

The jaws 13 and 14 have opposing semi-circular recesses to receive the work. Toothed dies having teeth facing in opposite direction are detachably mounted upon the jaws adjacent the base of the opening. A lip 20 extends from the mouth of the jaw 13, and is arranged to receive a bail 21 which is pivotally mounted upon a lip 22 on jaw 14. The structure is such that when the jaws are closed, bail 21 may be swung over lip 20 to hold the jaws in locked position. In order to limit the opening of the jaws, they are provided with stops 23 and 24 arranged to engage the spacing bolts 17 and 17'. A leaf spring 25 is secured to the side plates and bears upon the ends of bail 21 tending to hold the latter in closed position.

sition as shown in Fig. 1. An arm 26 is fixed to the bail and extends outwardly, it being for the purpose of turning the bail into releasing position against the action 5 of spring 25. Connected to the arm is a line 27 having its other end secured to the handle. The line is in such position that by a pull upon it the bail 21 may be swung into open or released position. A pull upon 10 the line 27 not only tends to release the bail but also to pull the jaw 14 into open position.

Pivots mounted upon the handle is a lever 28 having a cam head 29 with an 15 arcuate upper surface arranged to engage the lower surface of link 12 or 12'. The high spots of the cam surface are at the extreme edges. A detent pin 30 is mounted in the lever 28 and is arranged to engage 20 a recess in the handle 8, when lever 28 is in its central or neutral position.

The tool, preparatory to application to the work, has its parts in the position shown in Fig. 1. In this position, the links 12 25 and 12' rest against the cam head 29. The jaws may be opened by releasing the bail 21. This is accomplished by pulling upon line 27, turning the bail into the position shown in Fig. 5. A further pull upon the 30 line swings the jaw 14 into the position shown in dotted lines in Fig. 5. This permits the jaw 13 to swing outwardly, until the stops 23 and 24 on the jaws engage the bolts 17 and 17', thus, limiting the amount 35 of opening which is so designed as to permit the entrance of the work. Due to the shape of the lips the tool may be pressed against the work fully opening jaw 13. After the jaw has embraced the work as 40 shown in dotted lines in Fig. 5, the tool is pressed against the work causing the jaws to turn to the closed position shown in Fig. 6. The pull upon line 27 is released permitting the spring 25 to turn the bail into closed 45 position thereby locking the jaws. Suppose it is desired to turn the work to the left. The operator turns the handle from the position shown in full lines in Fig. 6 to that shown in dotted lines. The parts 50 are then in the position shown in Fig. 7. The cam head will have moved the link 12' upwardly and forced the die 19 into the work. Pressure upon the handle 8 in the direction of the arrow in Figs. 6 and 7 will 55 cause a pull upon link 12, which is conveyed through bail 21 to jaw 14. The greater the pull the more firmly the die bites into the pipe. The action of pressure upon the handle is shown in Fig. 7. If it is desired 60 to turn the pipe or work in the opposite direction, lever 28 would have been moved to the right to provide initial gripping of the pipe by die 18. The handle when turned toward the right would cause a pull 65 upon link 12', it being conveyed through

the jaw 14, bail 21 to jaw 13, thereby causing the die 18 to bite into the pipe. When it is desired to release the tongs, the lever 28 is swung into its neutral position thereby permitting the links and jaws to drop. Line 27 is then pulled upon bringing the bail 21 into releasing position. A further pull upon the line swings jaw 14 into open position and the tool may be pulled away 70 from the work. 75

What we claim is:

1. Tongs comprising in combination spaced plates, a handle pivotally mounted between said plates, opposing jaws mounted between said plates so as to permit pivotal 80 movement and limited lineal movement in said head axially of said handle, means connecting each jaw and the handle whereby turning the handle will push one jaw against the work and pull the other jaw 85 in the opposite direction, means to lock said jaws together, means mounted on said handle to initially push one of said jaws against the work.

2. Tongs comprising in combination spaced plates, a handle pivotally mounted between said plates, opposing jaws mounted between said plates so as to permit pivotal movement and limited lineal movement in said head axially of said handle, means connecting each jaw and the handle whereby turning the handle will push one jaw against the work and pull the other jaw 90 in the opposite direction, means to lock said jaws together, a lever pivotally mounted on 95 said handle and having a cam disposed to move said jaws, the contour of said cam being such that when swung to one side it will initially move one of said jaws against the work. 100

3. Tongs comprising in combination spaced plates, a handle pivotally mounted between said plates, opposing jaws mounted between said plates so as to permit pivotal movement and limited lineal movement 110 in said head axially of said handle, means connecting each jaw and the handle whereby turning the handle will push one jaw against the work and pull the other jaw in the opposite direction, said jaws being 115 provided with lips, a bail pivotally mounted on one lip and disposed to engage the other whereby to lock said jaws together, a spring tending to hold said bail in closed position, an arm on said bail whereby the latter may 120 be turned to release said jaws, a control line leading from said arm to said handle, means mounted on said handle to initially push one of said jaws against the work.

4. Tongs comprising in combination 125 spaced plates, a handle pivotally mounted between said plates, opposing jaws mounted between said plates so as to permit pivotal movement and limited lineal movement in said head axially of said handle, 130

means connecting each jaw and the handle whereby turning the handle will push one jaw against the work and pull the other jaw in the opposite direction, said jaws being provided with lips, a bail pivotally mounted on one lip and disposed to engage the other whereby to lock said jaws together, a spring tending to hold said bail in closed position, an arm on said bail whereby the latter may be turned to release said jaws, a control line leading from said arm to said handle, a lever pivotally mounted on said handle and having a cam disposed to operate said jaws, the contour of said cam being such that when swung to one side it will initially move one of said jaws against the work.

5. Tongs comprising in combination spaced plates, a handle pivotally mounted thereon between said plates, opposing jaws mounted between said plates so as to permit pivotal movement and limited lineal movement in said head axially of said handle, links one pivotally secured to each jaw and to said handle, means to lock said jaws together, dies in said jaws for biting into the work, a lever pivotally mounted on said handle and having a cam head disposed to engage the bottoms of said links, the contour of said cam being such that when said lever is swung to one side it will move one of said links to force a jaw with its die against the work and whereby turning the handle will place a tension upon the opposite link.

35. 6. Tongs comprising in combination spaced plates, a handle pivotally mounted between said plates, opposing jaws mounted between said plates so as to permit pivotal movement and limited lineal movement in said head axially of said handle, links one pivotally secured to each jaw and to said handle, said jaws being provided with lips, a bail pivotally mounted on one jaw and disposed to engage the other to lock said jaws together, a spring tending to hold said bail in closed position, an arm on said bail whereby the latter may be turned to release said jaws, a control line leading from said arm to said handle, dies in said jaws for biting into the work, a lever pivotally mounted on said handle and having a cam disposed to engage the bottoms of said links, the contour of said cam being such that when said lever is swung

to one side it will move one of said links to force a jaw with its die against the work and whereby turning the handle will place a tension upon the opposite link. 55

7. Tong comprising in combination spaced plates, opposing jaws mounted between said plates so as to permit pivotal movement and limited lineal movement in said head axially of said handle, links one pivotally secured to each jaw and to said handle, means to lock said jaws together, dies in said jaws for biting into the work, a lever pivotally mounted on said handle and having a cam of arcuate shape with the high spots at the sides for engaging the bottoms of said links so that when said lever is swung to one side it will move the link on that side and force the corresponding jaw with its die against the work and whereby turning the handle will place a tension upon the opposite link.

8. Tongs comprising in combination spaced plates, opposing jaws mounted between said plates so as to permit pivotal movement and limited lineal movement in said head axially of said handle, links one pivotally secured to each jaw and to said handle, said jaws being provided with lips, a bail pivotally mounted on the lip of one of said jaws and disposed to hook over and engage the other lip whereby to lock said jaws together, a spring tending to hold said bail in position, an arm on said bail whereby the latter may be turned to release said jaws, a control line leading from said arm to said handle, dies in said jaws for biting into the work, a lever pivotally mounted on said handle and having a cam head of arcuate shape with the high spots at the sides for engaging the bottoms of said links so that when said lever is swung to one side it will move the link on that side and force the corresponding jaw with its die against the work and whereby turning the handle will place a tension upon the opposite link. 95

In witness that I claim the foregoing I have hereunto subscribed my name this 19th day of November, 1923.

JOHN GRANT.

In witness that I claim the foregoing I have hereunto subscribed my name this 8th day of November, 1923.

STEWART L. CAMPBELL,
